UNITED STATES PATENT OFFICE.

FRANK O'NEILL, JR., OF PHILADELPHIA, PENNSYLVANIA.

FIBROUS PLANT DECORTICATING MACHINE.

1,420,136.

Specification of Letters Patent. Patented June 20, 1922.

Application filed April 18, 1918. Serial No. 229,358.

To all whom it may concern:

Be it known that I, FRANK O'NEILL, Jr., a citizen of the United States, and resident of Philadelphia, in the county of Philadelphia and in the State of Pennsylvania, have invented a certain new and useful Improvement 5 in Fibrous Plant Decorticating Machines, and do hereby declare that the following is a full, clear, and exact description 10 thereof.

My invention relates to machinery for decorticating various fiber bearing plants such as agave, sisal, abaca, pine-apple leaves, etc., and more particularly my object is to provide 15 a readily portable hand operated machine although its construction whereby the fiber can be recovered with a minimum of loss or injury is adaptable to larger machines, whether portable or stationary and 20 whether driven by other power than hand, and for the attainment of the objects of my invention which generally stated are, first, a machine of high efficiency and economy, and, second, a readily portable machine, my invention 25 consists in a decorticating machine constructed substantially as hereinafter specified and claimed.

In the accompanying drawings:

Fig. 1 is a top plan view of a small portable machine embodying my invention;

Fig. 2 is a vertical longitudinal section.

Fig. 3 is a cross section on the line 3—3 of Fig. 1 on a larger scale;

Figs. 4 and 5 are detail views in cross section showing two constructions of decorticating blades that may be used;

Fig. 6 a cross section of one of the shredding blades;

Fig. 7 is a detail view in elevation of a portion of one of the shredding blades;

Fig. 8 is a detail view showing the feed controlling mechanism.

Describing the invention illustrated in the drawings it is of a size enabling it to be readily lifted and transported from place to place according to the requirements of the work and it therefore has a frame composed of parallel longitudinally extending side bars 64 whose extremities are formed into lifting handles 65 and legs 66 at each end preferably foldable upon which, when extended the machine rests.

At one end of the machine is a feed table which consists of a light frame of iron composed of parallel side bars 67 and a trans-

verse bar 68 connecting the side bars at their outer ends and an apron 69 of flexible material which at one end is attached to said cross bar and at its other end is fastened to a shaft or drum 70 journaled at its opposite ends in the side bars 64. The feed table frame is longitudinally slidable between the side bars 64 so as to enable the table to be slid wholly in between said side bars to render the machine as compact as possible for transportation, or rather the side bars of the feed table frame are thus slideable for the apron is wound on the shaft or drum 70 when it is desired to reduce the bulk of the machine. Said winding shaft is provided at one end with a crank 71 for revolving it. A bracket or arm 72 projecting inward from each side bar 64 supports the adjacent side bar of the feed table in its sliding movement. Just beyond the roller or drum 70 is a pair of upper and lower shredding or slitting rollers 73, one of which is journaled in fixed bearings on the side bars 64 and the other in vertically movable spring pressed 80 bearings so that the two rollers are pressed yieldingly together. Said rollers consist of spaced thin cutting disks mounted on a shaft that are kept clean by brushes 74. Beyond the shredding rollers is a pair of upper 85 and lower pressure flattening feed rollers 75, also mounted respectively in fixed and spring pressed bearings, and which are kept clean by scrapers 76.

From the feed rolls the plants are delivered to and subjected to the action of devices which bend the plants first in one direction and then in the other so as to fracture the woody portions of the plant and loosen the same from the fiber and subject the same 95 to a scraping treatment the result being the separation of the fiber by a gentle yet efficient treatment that avoids injury and loss. Said device consists of two similar endless series of thin plates of blades 76 and coacting bars 77, blades and bars of a series alternating, and acting on the plants in different planes, and a blade of one series coming opposite and cooperating with a bar of the other series. The blades and bars of each 100 series are carried by sprocket chains or belts 78 which pass over sprocket wheels 79 on parallel shafts 80 supported in bearings upon the side bars 64 of the frame. To render the action a gentle one a cushioned 110 support for the plants under the thrust of

the blade is provided by mounting the coacting bar on springs 81, which yieldingly press the bar towards the blade, and blades and bars are also pressed yieldingly together by means of a spring supported straight bar or rail 82 for each series over which the sprocket chains travel during the time the blades and bars are coacting.

For imparting the traveling movement to 10 the two series of bars and blades, a crank shaft 83 is journaled in bearings at the far end of the machine and provided with a crank 84 on each end and upon said shaft is a pinion 85 which meshes with a gear 86 on 15 one of the shafts 80 and said gear 86 in turn meshing with a similar gear 88 on the adjacent shaft 80.

Upon each of the other shafts 80 towards the feed end of the machine are pinions 20 89 and 90 respectively with either of which is adapted to mesh an idler gear 91 constantly in mesh with a gear 92 on the upper feed roll shaft and thus motion is transmitted to the feed rolls and the latter turned 25 in one direction or other according to which of the pinions 89 and 90 the idler meshes.

Said idler gear is journaled in a lever 93 which is pivoted on the upper feed roll shaft so as at all times to maintain the idler gear 30 in mesh with the gear on said shaft and a notched bracket 94 is provided to engage the idler gear swinging lever to hold the latter in position to mesh the idler gear with either pinion 89 and 90 or with neither of 35 them should it not be desired to drive the feed rolls from either of said pinions 89 and 90.

On the upper feed roll shaft is a sprocket wheel 95 which is connected by a chain 96 40 to a sprocket wheel 97 on the upper shredding roll shaft and thus motion is imparted to the latter, the two shredding rolls being geared together by spur gears 98. Spur gears 99 gear the two feed rolls together.

45 As best shown in Figs. 4 and 5, the decorticating blades 76 are presented to the plants in a slanting position or at an oblique angle, and the slant is in the direction of travel of the blades in coacting with their bars 77. 50 Inasmuch as in the operation of the machine, the direction of travel of the blades is reversed, this slantwise position of the blades during action may be secured either by the double oppositely inclined arrangement of 55 stationarily mounted blade shown in Fig. 5, or as shown in Fig. 4, by pivoting the blades 76 on its longitudinal axis at its ends to the sprocket chains so that it may swing to the desired angle dependent upon the direction 60 in which it is traveling, and such swinging of the blade may be automatically accomplished, and the blade maintained during action in the position to which it may be swung by causing its heel to slide upon the 65 adjacent surface of the bar 82.

If desired hackling members or devices may be applied to the sprocket chains or belts 78, the hackling member being in the form of a cross bar 100 for cooperating with 70 a bar 77 carried by the opposing belt 78 and having on its edge towards the bar 77 short teeth 101 which will be self clearing. Said hackling bars are provided to act on both sides of the material.

At one end of the machine farthest from 75 the feed table I provide a clamp consisting of a pair of parallel bars 102 one of which is stationarily supported on the side bars 164 of the frame, while the other is movably supported so that it may be moved towards and from its mate, and thus opened for the insertion of the cleaned end portions of the fiber, and then clamped thereupon, rocking cams 103 being provided for this purpose 80 and having each a handle 104 by which it may be rocked. The opposite fiber engaging faces of the clamping bars are preferably corrugated so as to take a firm grip upon the plants and to hold them under the pull of 85 the decorticating devices when acting upon 90 the plant.

In the use of a machine having the construction shown in the drawings the plants or leaves tip end first are passed first to the shredding rolls and then to the feed rolls 95 which are so geared that they catch and feed the leaves forward and into the decorticating devices, the movement of the various parts of the machine being affected by the cranks on the crank shaft at the far end of the machine. The speed of the bars and blades of 100 the decorticating devices is faster than the speed of the feed rolls so that there is a longitudinal scraping action on both sides of the leaves simultaneously, such operation 105 beginning with the tops of the leaves and proceeding towards the butt ends. The speed of this action is a slow one and hence no jerking and objectionable straining on the fibers occurs.

When the leaves have passed almost through the feeding and flattening rolls, the lever 93 is raised to place the idler gear 91 in a neutral position so as to stop the feeding 110 action and then the action of the decorticating mechanism is continued until all portions of the leaves or plants within their reach are perfectly clean. When that is accomplished, the operator opens the clamp bars, lowers the lever 93 to again restore the meshing engagement of the gears by which motion is transmitted to the feed rolls and resuming the turning of the cranks, the feed of the material continues until the same passes beyond the grip of the feed rolls, and the clean 115 forward end of the fibers can be inserted between and grasped by the clamping bars, and then the crank is turned in the opposite direction to cause the decorticating blades and bars to act upon the butt end portions of the 120 fibers. 125

plants which up to that time have not been within reach of the decorticating devices.

Having thus described my invention what I claim is:

- 5 1. A machine of the class described having decorticating devices comprising means for subjecting the plants alternately to a combined bending and scraping action, said means comprising two series of blades and
- 10 members with blade opposing surfaces, the blades and members alternating in succession, means for moving said blades and members lengthwise of the plants, and feed rolls having a relatively slower motion than that
- 15 of said blades and members.
2. A machine of the class described having decorticating devices comprising means for subjecting the plants alternately to a combined bending and scraping action, said
- 20 means comprising two series of blades and members with blade opposing surfaces, the blades and members alternating in succession, means for moving said plants and members lengthwise of the plants, and feed rolls
- 25 having a relatively slower motion than that of said blades and members, the direction of revolution of said rolls being changeable at will.
3. A machine of the class described having
- 30 traveling decorticating devices, means for feeding the material to be operated on to said devices at one end thereof, and stationarily mounted means to clamp the material situated at the opposite end of said devices.
- 35 4. A machine of the class described having traveling decorticating devices, feed rolls for delivering the material to said devices at one end thereof, and a stationarily mounted clamp situated at the other end of said devices operable at will to engage the material.
- 40 5. A machine of the class described having traveling decorticating devices arranged in two endless series, and means for causing

movement of said two series of devices alternately in either direction. 45

6. A machine of the class described having traveling decorticating devices arranged in two endless series, means for causing movement of said two series of devices alternately in either direction, and means for connecting 50 and disconnecting the feed rolls with the traveling decorticating devices.

7. A machine of the class described having opposing traveling decorticating members one of which has a blade form and which 55 while coacting with its opposing member inclines forward in the direction of its travel, the direction of travel of said members being reversible.

8. In a machine of the class described, the 60 combination of decorticating devices, a frame having side members, a feed table comprising a longitudinally shiftable frame, a flexible apron attached at one end to said frame, and a winding roller to which the other end of 65 said apron is attached.

9. A machine of the class described having traveling decorticating devices and rotatable feed rolls, and means under manual control for moving the decorticating devices 70 at a faster speed than that of the feed rolls.

10. A machine of the class described having traveling decorticating devices, means for feeding material to the latter, and a slitting member independent of and located 75 in advance of the feeding means.

11. A machine of the class described having a traveling decorticating device, means for feeding material to the latter, and slitting means located in advance of the feeding 80 means and comprising a pair of opposed rollers, each having a transversely extending series of spaced cutting disks.

In testimony that I claim the foregoing I have hereunto set my hand. 85

FRANK O'NEILL, JR.
